 American District Telegraph Company, Jersey
 City, N. J., a corporation of New Jersey

Application June 15, 1940, Serial No. 340,696

13 Claims. (Cl. 177—380)

This invention relates generally to signalling systems and more particularly to those systems wherein it is desirable that code signals received at a central office be retransmitted either to an audible signal receiver or to a recorder or indicator at a remote point such as for example a fire or police headquarters.

In some forms of signalling systems the signals, whether or not they are in the nature of alarm signals, are recorded at the central office where they are received, and in addition they may be retransmitted either manually or automatically to a headquarters such as fire or police headquarters. It is desirable in such systems to provide a retransmitting device which is simple in its organization, flexible and positive in its action. It is also desirable that such retransmitting systems be capable of transmitting a code which is either the same as the received code or different in the number of digits and the number of rounds which are retransmitted. Therefore, it is further desirable to provide a simple arrangement for transmitting a code comprising any desired number of digits and any desired number of signal rounds.

Accordingly, the principal object of this invention is to provide a simple and efficient signal transmitter.

A further object of this invention is to provide a code transmitter in which the number of rounds may be determined and transmitted at the will of the operator, and in which any code number may be transmitted from 1 to 9,999.

A still further object of this invention is to provide a signal transmitter which is simple in operation and economical in maintenance.

Further objects and advantages of this invention will be apparent to those skilled in the art upon consideration of the following specification and the accompanying drawing, wherein:

The single figure of the drawing is a circuit diagram which illustrates a preferred embodiment of the invention.

This invention is adapted for use in any signalling system such as that comprising a transmission line including a number of transmitting stations for transmitting code signals and a central office where such code signals are received and recorded or otherwise indicated. In some installations it is not feasible to provide automatically operated apparatus for retransmitting such signals to local audible signal devices or remote audible signal devices and recording devices. Therefore, in accordance with this invention, a signal transmitter is provided which is

adapted to transmit any desired code signal and any desired number of rounds of such a signal.

The invention will be described generally in order to convey a preliminary understanding thereof. When a code signal is to be transmitted, the operator sets up that signal on the code keyboard 12, which comprises four rows of push buttons or other circuit closing or opening devices, the push buttons being arranged in a thousands row, a hundreds row, a tens row, and a units row, whereby a four digit code signal may be set up by selecting and operating a button from each of the rows. The transmission is actually initiated by momentary actuation of start button 1, which in turn operates an impulse generating circuit comprising the relays 5 and 7, these relays being arranged to short-circuit one another in succession. The relay 5 is provided with a number of switching contacts to control a code selecting switch ST which is made up of three separate banks of fifty contacts each and which is stepped intermittently in accordance with the successive operations of relay 5. Bank 1 of the selecting switch performs a switching function in conjunction with the relay 5 and a switch relay 9, while bank 2 of the selecting switch actually selects the code which is set up on the keyboard 12. Bank 3 of the selecting switch establishes a shunt circuit around the starting button 1, whereby the battery current is maintained across the starting button after its momentary actuation.

The push buttons are connected to the second bank of the selector switch ST in such a manner that the zero button in the thousands row is connected to contact 2 of the selector, and the other buttons are connected in sequence to the following contacts up to contact 11, contact 12 being left blank to determine the end of the thousands digit. The hundreds row of buttons is connected in sequence to contacts 13 to 22 of the selector switch, contact 23 being left blank to determine the end of the hundreds digit, and the buttons in the tens row are connected in sequence to contacts 24 to 33, contact 34 being left blank. The buttons in the units row are connected to contacts 35 to 44 of the switch, while contact 45 is directly connected for the purpose of carrying the operation of the circuit over into a subsequent round.

The switching operations are controlled through a number of parallel circuits. When the code has been set up and the transmitter started and selector ST has reached position 2, it is stepped in self-energizing fashion through the

circuit comprising bank 2, the digit selecting button and contacts 5 and 7 of relay 9 through stepping magnet STS. When the rotating arm or wiper of switch ST2 connects a contact connected to an operated pushbutton, the short circuit across the relay 9 is removed allowing this relay to operate through a circuit which extends through bank ST1 and contact 2 of relay 5, the stepping operation then being controlled by contact 1 of relay 5 so that the switch ST is stepped slowly in accordance with the operation of relay 5 to count the first digit of the code. At the end of this digit switch ST reestablishes a shunt circuit around relay 9 so that the self-energizing circuit again causes switch ST to make a series of fast steps until the button in the second row is found by bank 2 of the switch. The counting function is continued in this fashion, relay 9 being energized by the action of switch ST to cause transmission of each code digit.

Actual transmission of the signals is controlled by relay 5 and relay 9, relay 9 closing the transmission circuit at its contact 1 and relay 5 causing transmission to receiver 15 of the code digits at its contact 4. Thus the relay 9 prepares the transmission circuit and relay 5 controls code transmission as determined by bank 2 of selector ST.

The selector CS is a round counting selector which controls transmission of a plurality of rounds under the control of the buttons B2, B3, and B4. The relay 9 through its contact 2 establishes a first circuit for energizing the switch CS whereby one round is always transmitted. If for instance three rounds are to be transmitted, the button B3 is operated to open the stepping circuit for switch CS whereby at the end of the third round the switch returns to its normal position and opens the off-normal contact which it controls through a cam, to thereby completely deenergize the transmitter and stop its operation.

A detailed description of the operation of the circuit will now be given in connection with the drawing.

Circuit operation

Let us assume that a three round code of 4-5-2-3 is to be retransmitted. The fourth button in thousands row shall be pressed, the fifth in the hundreds row, the second in the tens row and the third in the units row. The round selecting button (in this case B3) shall be pressed.

The momentary closing of the pushbutton switch 1 applies minus battery to the coil of relay 5, through the circuit traced from minus battery, through the starting button 1, through the coil of relay 5 and resistor 6 to plus battery. The operation of relay 5 opens the contact 5, removing the obvious shunt across the relay 7, thereby allowing this relay to be energized through a similar circuit to that traced for the operation of relay 5, from minus battery through relay 7, resistor 8 to positive battery. The operation of relay 7 applies a shunt by its contact 1 across relay 5, which causes this relay to become deenergized. Relay 5 again in turn applies the shunt, by its contact 5, across the relay 7, which again releases. This completes one cycle of operation of the pulse generating relays 5 and 7 and this cycle of pulsing is repeated as long as power is supplied from battery.

Upon the first operation of relay 5, at the start of a transmission, a circuit is closed from minus through the starting button 1, through code selector ST, bank 1, at contact 50, through contact 1 of relay 5 upon its first closing, through selector

stepping magnet STS to plus battery, thereby actuating the stepper armature. Upon the first shunting and release of relay 5, STS becomes deenergized, advancing the selector ST to position 1.

5. Selector bank ST3 thereafter shunts pushbutton 1 and maintains the battery connection until the 50th step of the round is completed. At position 1, upon the second operation of relay 5, selector stepping magnet STS is energized through a circuit traced through bank 1, position 1 of selector ST, make contact 3 of relay 5, back contact 7 of relay 9, interrupter contact of stepping magnet STS, stepping magnet coil STS, to plus, selector ST advancing to position 2 on the break of the interrupter contact of stepping magnet STS.
10. At position 2, the winding 1 of the relay 9 is connected to minus battery but does not operate due to the shunt across its winding by the contact of bank 2 of selector ST at position 2, through the button 8 of the thousands row in switch 12, and back contact 5 of relay 9.

At position 2, the previous stepping circuit for ST is opened on bank 1 but a second circuit is closed from minus battery through bank 2 of ST, through the closed pushbutton 0 on the key switch 12, through break contacts 5 and 7 of relay 9, interrupter contact of magnet STS of the selector and the selector stepping magnet STS to plus battery. When the selector becomes energized, it breaks its own stepping circuit at the contact of stepping magnet STS, thereby advancing the selector to position 3. This self-stepping circuit is completed by the various buttons 9, 8, 7, 6, etc. on the thousands row, the selector advancing to a point at which there is an open caused by the operation of a button (for the code being discussed, this will be button 4 connected to position 8 of bank 2 of ST).

30. When the selector ST reaches position 8, the shunt across the winding 1 of relay 9 is removed, due to the open at button 4, relay 9 therefore operating through the circuit traced from minus through bank 1 position 8, through winding 1 of relay 9, through break contact 2 of relay 5 and back contact 7 of relay 9, through the interrupter contact and coil STS to plus. The stepper will not be advanced at this time due to the fact that the current through its winding is limited to a low value by the added resistance of winding 1 of relay 9. The operation of the make-before-break contacts 6 and 7 of relay 9 causes this relay to lock in through its coil and the resistance winding 2 to plus battery.
35. The operation of relay 9 at this time closes a new stepping circuit for the selector ST from minus battery, through make contact 3 of relay 9, through pulsing contact 1 of relay 5, through the coil STS to plus battery. Contact 2 on relay 9 at this time closes a circuit from minus battery, through contact 2 of relay 9, through position 11 (normal home position) on bank 1 of counting selector CS through the interrupter contact of stepping magnet CSS, make contact 5 of relay 5 and stepping coil CSS to plus. Selector CS becomes energized but immediately breaks into its own circuit and advances one step. At position 1 there is no power available for further self stepping due to the open in the circuit at round button 3. The cam operated off-normal contacts CSC of switch CS shunt the starting button 1 and bank ST3 establishing a second circuit for maintaining battery connection.

40. The operation of the break contact 5 of relay 9 opens the shunt circuit of bank 2 caused by the remainder of the pushbutton keys in one row.

- 60.
- 65.
- 70.
- 75.

Contact 4 of relay 9 shunts across contact 2 of relay 5 and locks in relay 7. The selector ST will then be stepped by the operation of the contact 1 of relay 5, advancing the selector to position 12, making in all four slow steps for the first digit of the code. At position 12, the circuit through the winding 1 of relay 9 will be interrupted at bank 1, position 12, thereby releasing it but a stepping circuit previously traced through bank 1 and contact 3 of relay 5 is completed, the only difference being at this time through position 12 instead of position 1. Upon reaching position 13, a similar shunt circuit is completed across the winding 1 of relay 9 and an interrupter circuit is again set up for the stepping coil STS similar to that previously described at position 2. The selector ST will become self-interrupting and advance to a position as determined by the open in the pushbuttons connected to bank 2; in the case of the second digit for the code discussed this will be button 5 connected to position 18 of ST2. At this point relay 9 will energize again and the selector ST will make five slow steps as determined by the operation of the pulsing contact 1 of relay 5.

The remainder of the digits of the code are transmitted in a manner similar to that previously described.

Upon reaching position 45 of the selector at the end of the last digit, the relay 9 releases, as previously described, and an additional step is made from 45 to 49, through a circuit which may be traced through contact 45 of bank ST2, through back contact 5 of relay 9, break contact 7 of relay 9, interrupter contact and coil of STS to plus battery. At positions 46 to 50 five steps are made through the original stepping circuit described through bank 1, through positions 46 to 50 and contact 1 of relay 5, and coil STS to plus battery. This permits an interval between rounds.

At position 49, counting selector CS is energized through the circuit traced from minus battery, through the ST selector bank 2 to position 49, through make contact 6 of relay 5 and coil CSS to plus battery, advancing to position 2 on the release of relay 5.

When selector ST reaches position 50, power is still applied from battery through the cam operated contacts of CS and therefore a second round of signals is started.

At position 49 of this round, selector CS advances to position 3. At this point a self-stepping circuit for CS is established from battery through button B4, position 3 of bank 1 of CS, the interrupter contact of coil CSS, make contact 6 of relay 5 and coil CSS to plus, causing the selector to advance to position 4. A similar self-stepping circuit through points 4 to 9 of bank 1 advances the selector CS to position 10.

Following this, the third round is transmitted. When selector ST reaches position 49, selector CS is energized through a circuit previously traced, moves to position 11 on the release of relay 5, and opens its cam operated contacts CSC. At the same time selector ST advances from 49 to 50 and removes the connection to battery through bank 3. Therefore the transmission stops and restoration of the code keyboard push buttons and the round selecting buttons to their normal closed positions leaves the transmitter in its normal condition and in condition for subsequent selection of a new code.

Retransmission of either 1, 2 or 4 rounds is accomplished in a similar manner, the control

by buttons B2, B3 or B4 determining the stepping circuit for selector CS.

Coding operation

From the previous description it will be recalled that CS moves from its normal home position 11 on the first operation of relay 9. Also, that this relay operates at the start of code transmission and remains energized during each digit during which time the equipment is controlled by the operation of relay 5. Therefore the coding circuit will be closed each time contact 4 of relay 5 closes, for a number of operations depending on the code set up.

The transmitting system as described above may be adapted for transmission of signals to any form of signal receiving device. For purposes of illustration a conventional signal recorder 15 is shown connected in a series with a source of current, contact 4 of relay 5, contact 1 of relay 9, contact 11 of switch CS, and tapper button 16. Thus a code of four digits or less may be transmitted to the signal receiver 15 under the control of either contact 4 of relay 5 or the manually-operated tapper button 16.

From the above description it is evident that this invention provides a transmitting device which is adapted to transmit code signals comprising one or more digits and also comprising one or more successive rounds. It is obvious that the push-buttons on the keyboard may be replaced by any form of manual or automatic circuit opening device whereby the transmitter may be either manually or automatically operated from a remote point in response to signals received from signaling systems such as those in everyday use for supervision of fires, burglary, or watchman's supervisor signal systems.

Further modifications of this invention will be evident to those skilled in the art, and therefore it is desired that this invention shall be limited only by the prior art and the scope of the appended claims.

I claim:

1. In an impulse code transmitter for transmitting impulses over an electric circuit, selector means including a stepping switch having a series of contacts and a switch wiper engaging said contacts, digit keys connected to the respective contacts for setting up the code to be transmitted, pulsing means for operating said switch wiper to close control circuits successively through said digit keys and means controlled by said control circuit and the particular key that is operated for transmitting impulses over said first-mentioned circuit during subsequent steps of the switch, said last-mentioned means including said pulsing means.

2. In an impulse code transmitter for transmitting impulses over an electric circuit, a step-by-step switch having a series of bank contacts, digit keys connected to the respective contacts for setting up the code to be transmitted, pulsing means for operating said switch to close circuits successively through said digit keys and means controlled by the particular key that is operated for transmitting impulses over said circuit during subsequent steps of the switch, said last-mentioned means including said pulsing means, said step-by-step switch and a relay having a winding connected to contacts of the respective digit keys, contacts of said relay being interposed in the transmitting circuit.

3. In an impulse code transmitter for transmitting impulses over an electric circuit, a count-

ing step-by-step switch having a series of bank contacts, digit keys connected to the respective contacts for setting up the code to be transmitted, an impulse generator for operating said switch to close stepping circuits successively through said digit keys for stepping said switch and means controlled by the particular key that is operated for transmitting impulses over said circuit during subsequent steps of the switch, said last-mentioned means including said pulsing means and contacts operated thereby, said step-by-step switch and a relay having a winding shunted by contacts of the respective digit keys, certain contacts of said relay being interposed in the transmitting circuit whereby an open digit key removes the shunt from said winding and the relay operates.

4. In a transmitting circuit, a source of impulses, a transmitting circuit operated by the source of impulses, a receiver connected thereto, circuit controlling means between the receiver and the transmitting circuit, a relay for actuating the circuit controlling means, a plurality of groups of code keys each key being adapted to control the relay and transmission of a digit, a selector means connected in series with the keys whereby code transmission starts when the selector establishes a connection to an operated key and a second selector for controlling actuation of the relay at the end of a digit, whereby code digit transmission is started by the first selector and terminated by the second selector.

5. In a transmitting circuit, a source of impulses, a transmitting circuit operated by the source of impulses, a receiver connected thereto, circuit controlling means between the receiver and the transmitting circuit, a relay for actuating the circuit controlling means, a plurality of groups of code keys each key being adapted to control the relay and transmission of a digit, a selector bank the contacts of which are connected to the code keys for switching successively from key to key within each group of keys for starting operation of said relay when the selector establishes a connection to an operated key and a second selector in circuit with the first selector for controlling actuation of the relay at the end of a digit whereby code digit transmission is started by the first selector and terminated by the second selector.

6. In an impulse code transmitter for transmitting signals, a key controllable code selector including movable switch wipers and cooperating banks of contacts for setting up a code and controlling its transmission, a key controllable counting selector for controlling the number of rounds of code to be transmitted, an impulse generator for driving the selectors, a current source, a manually operable switch for momentarily applying starting current from said source to said impulse generator, means including a bank of contacts of the code selector for maintaining a connection to the current source until a complete code has been transmitted and switch means operated by the counting selector for continuing the connection through a number of rounds of code.

7. In an impulse code transmitter for transmitting impulses over an electric circuit, a stepping switch having a series of bank contacts, a stepping magnet, an interrupter contact controlled by said magnet, digit keys connected to the respective contacts of the stepping switch and to each other which when operated set up a code to be transmitted, switching contacts for establishing a circuit through the stepping switch,

the keys, the stepping magnet and its interrupter contact whereby the stepping switch is initially self-stepping through each closed digit key, a switching relay connected in shunt to the stepping switch and the digit keys which becomes actuated and locked when the stepping switch establishes a connection to an open digit key, and which actuates the said switching contacts to break the self-stepping circuit, an impulse generator, a second stepping circuit including switching contacts in series with the stepping magnet of the stepping switch and controlled by the impulse generator and the switching relay whereby the stepping switch steps and counts successive impulses from the generator, a transmitting circuit including contacts controlled by the impulse generator and the switching relay whereby counted impulses are transmitted as a code digit and a second stepping switch controlled by the same stepping magnet for actuating the switching relay at the end of the digit which in turn actuates its contact in the second stepping circuit and its contact in the transmission circuit to terminate transmission of the digit.

8. In an impulse code transmitter for transmitting impulses over an electric circuit, a stepping switch having a series of bank contacts, a stepping magnet, digit keys connected to the respective contacts of the stepping switch and to each other which when operated set up a code to be transmitted, switching contacts for establishing a circuit through the stepping switch, the keys, the stepping magnet and its interrupter contact whereby the stepping switch is initially self-stepping through each closed digit key, a switching relay connected to the stepping switch and the digit keys which operates when the stepping switch establishes a connection to an open digit key, and which actuates the said switching contacts to break the self-stepping circuit, an impulse generator, a switch controlled by the switching relay for energizing the stepping switch whereby it counts successive impulses from the generator, a transmitting circuit including contacts controlled by the impulse generator and the switching relay whereby counted impulses are transmitted as a code digit and a second switch for actuating the switching relay at the end of the digit to terminate transmission of the digit.

9. In an impulse code transmitter for transmitting impulses over an electric circuit, a stepping switch having a series of bank contacts, digit keys connected to the respective contacts of the stepping switch which when operated set up a code to be transmitted, a switching relay connected to the stepping switch and the digit keys which becomes actuated when the stepping switch establishes a connection to an operated digit key, an impulse generator, a second circuit including switching contacts in series with the stepping switch and controlled by the impulse generator and the switching relay whereby the stepping switch steps and counts successive impulses from the generator, a transmitting circuit including contacts controlled by the impulse generator whereby counted impulses are transmitted as a code digit and a second switch for actuating the switching relay at the end of the digit to terminate transmission of the digit.

10. In an impulse code transmitter for transmitting impulses over an electric circuit, a selecting means having a series of contacts, digit keys connected to the respective contacts of the selecting means which when operated set up a code to be transmitted, a switching means con-

nected to the selecting means and the digit keys which becomes actuated when the selecting means establishes a connection to an operated digit key, an impulse generator, a second circuit including switches connected with the selecting means and controlled by the impulse generator and the switching means whereby the selecting means counts successive impulses from the generator, a transmitting circuit including transmitting means controlled by the impulse generator whereby counted impulses are transmitted as a code digit and a second switch for actuating the switching means at the end of the digit to terminate transmission of the digit.

11. In a transmitting circuit, an impulse generator, a source of current, means for connecting the source to start the generator, a pair of transmitting contacts operated by the impulse generator, a receiver connected thereto, switching contacts connected between the receiver and the transmitting contacts, a switching relay for controlling the switching contacts, a shunt around the switching relay comprising a plurality of groups of normally closed push-button switches each switch being adapted to be opened to control transmission of a digit, each group being assigned to control the transmission of a given digit of a code signal, a selector switch comprising groups of contacts connected in series with the groups of push-button switches whereby code transmission starts when the shunt is broken and the switching relay operates to close the switching contacts, a second selector controlled by the first selector for preparing a circuit through the switching relay and breaking such circuit at the end of a digit, whereby code transmission starts when the shunt circuit is removed by the first selector and the second selector operates the switching relay which in turn completes the transmission circuit until a digit is transmitted.

12. In a transmitting circuit, an impulse generator, a pair of transmitting contacts operated by the impulse generator, a receiver connected

thereto, switching contacts connected between the receiver and the transmitting contacts, a switching relay for controlling the switching contacts, a shunt around the switching relay comprising a plurality of groups of normally closed push-button switches each switch being adapted to be operated to control transmission of a digit, each group being assigned to control the transmission of a given digit of a code signal, a selector switch comprising groups of contacts connected in series with the groups of push-button switches whereby code transmission starts when the shunt is broken and the switching relay operates to close the switching contacts, a second selector for preparing a circuit through the switching relay and breaking such circuit at the end of a digit, whereby code transmission starts when the shunt circuit is removed by the first selector and the second selector operates the switching relay which in turn completes the transmission circuit until a digit is transmitted.

13. In a transmitting circuit, an impulse generator, a pair of transmitting contacts operated by the impulse generator, a receiver connected thereto, switching contacts connected between the receiver and the transmitting contacts, a switching relay for controlling the switching contacts, a circuit for normally disabling the switching relay comprising a plurality of groups of normally closed push-button switches each switch being adapted to control transmission of a digit, a selector means comprising contacts connected in series with the push-button switches whereby code transmission starts when the disabling circuit is operated by the selector means and the switching relay operates to control the switching contacts, a second selector means for controlling the switching relay and operating it at the end of a digit, whereby code transmission starts under control of the first selector and the second selector operates to in turn terminate the transmission of a digit.

MANFRED W. MUEHTER.
